CARBOHYDRATE-BORIC ACID SALTS OF
AMINO AROMATIC BASES

David Curtis, New York, N. Y.

No Drawing. Application July 13, 1945,
Serial No. 604,975

9 Claims. (Cl. 260—209)

1

The present invention relates to a series of new amino-aromatic salts, and, more particularly, to amino-aromatic salts of a boric acid complex with a carbohydrate.

It is the object of the present invention to provide a series of new amino-aromatic salts which are of increased solubility.

It is another object of the present invention to provide a new series of salts of the character described which have increased stability in solution.

It is a further object of the present invention to devise methods for preparing the salts of the present invention.

It is the general object of the present invention to devise methods and means for imparting increased solubility and greater stability in solution upon amino-aromatic bases and their boric acid salts than normal for such bases and salts in a particular solvent.

It is known that certain soluble carbohydrates have the power of activating boric acid in solution to a greater degree of dissociation than normal, thus producing strongly acid solutions of boric acid. Presumably, these carbohydrates form complexes with the boric acid in solution, of an ester nature, which are strongly acidic.

I have found that these boric acid-carbohydrate complexes are capable of forming salts with amino-aromatic bases much more easily than the ordinary boric acid and with lesser quantities of boric acid. I have also found that such salts have increased degrees of solubility in water and in other solvents in which the basic substances are either insoluble or have a limited degree of solubility.

It is believed that it is the multiplicity of hydroxyl groups present in the carbohydrate molecules and the favorable disposition of such hydroxyl groups to the formation of ring systems with boric acid that leads to the formation of the complexes.

Maganini, An. 1890, p. 1357; 1891, p. 251, cites mannitol and dulcitol as increasing the conductivity of boric acid in solution.

J. Boeseken et al., in Rec. Trav. Chim., 1911, v. 30, pp. 392-400, states that the two OH groups of polyhydroxy compounds should be in the alpha position to one another and should be in the same plane, in order to permit the formation of ring combinations with boric acid.

E. B. R. Pridgeau, Z. Anorg. Chem., 1913, v. 83, pp. 362-68, shows that boric acid may be titrated with the addition of mannitol.

Z. Anorg. Alg. Chem., v. 142, pp. 83-110, 1925, shows that boric acid readily forms esters with

2

mono and polyhydroxy alcohols with increasing acidity and conductivity.

Various carbohydrates may activate boric acid to a different degree of acid potency.

5 Ukraine Klin. Zhur., v. 11, pp. 433-44, 444-5, 1936, shows dulcitol, xylose, mannose and arabinose as increasing the degree of dissociation of boric acid. The same publication, in vol. 8, pp. 307-15, 1935, cites fructose to be as good as mannitol in increasing dissociation of boric acid and maltose, lactose, glucose, erythritol and galactose as increasing ionization of boric acid, in the order given, having a lesser effect than fructose or mannitol; two moles of mannitol per one mole of boric acid producing the magnitude of the effect.

10 I. Ageno et al., Gazz. Chim. Ital., 43, 2, 163-74, state that the electrolytic dissociation of mannitol-boric acid is of the order of monobasic organic acids (i. e. much stronger than that of boric acid) and is proportional to the concentration of mannitol. They conclude that mannitol and boric acid unite in the proportion of 1:1.

15 J. C. Irvine et al., J. Ch. Soc., v. 107, pp. 1221-25, 1915, states that Boeseken's conclusions that the joint increase in the conductivity shown by certain OH compounds in the presence of boric acid is only encountered when two OH groups are attached to adjacent carbon atoms and are 20 arranged on the same side of the carbon atoms, in the same plane, have been extended to the study of partially methylated derivatives of mannitol, thus confirming the structure

It was shown that the OH groups 1 and 2 are primarily responsible for the increase in conductivity.

40 J. Boeseken et al., in Rec. Trav. Chim., v. 30, pp. 392-406, has shown that pentaerythritol $(\text{CH}_2\text{OH})_3\text{C}(\text{CH}_2\text{OH})$ is capable of forming two ring systems with boric acid and its influence on 45 the conductivity of boric acid is enormous; which would indicate that the two end OH groups are in a favorable position to form the ring systems with the boric acid.

Jones, in Amer. J. Sci., 1899, v. 7, p. 147, shows 50 it is a well known fact that the addition of mannitol and other polyhydroxy alcohols to a water solution of boric acid results in the formation of a strong acid in the liquid. If sufficient mannitol is present boric acid will act as a monobasic acid as regards the titration with NaOH solution.

55 Vignon, Ann. Chim. Phys., 1874, v. 2, p. 433,

observes that upon the addition of borax to a solution of mannitol, there was an increase in the optical activity of the solution; also when boric acid was added. This suggested the formation of some compound of mannitol with boric acid.

Dunston, Phar. J., 1883, v. 14, pp. 41, obtained a compound by the fusion of mannitol and borax.

Maganini, in Z. Physikal. Chem., 1890, 6, 58, drew the conclusion that a compound was formed between one mole of mannitol and 3 moles of boric acid.

J. J. Fox et al., J. Chem. Soc. of London, v. 33, p. 1075, 1911, show the isolation of mannitolboric acid, 1:1 mannitol and boric acid, and also show that an excess of either boric acid or mannitol favors the formation of this compound, $C_6H_{15}O_8B$.

Jo Yun Tung et al., in the J. Chinese Chem. Soc., v. 9, pp. 125-33, 1942, states that, generally, the boric acid complex with a carbohydrate may be represented as "EAn," where E is the borate ion, n is 2, and A may be mannitol, xylose, fructose, arabinose; and the structural formula of the complex is represented by

H. Schaefer, in Z. Anorg. Allgem. Chem., 247, 96-112, 1941, states that activating boric acid by different carbohydrates, such as mannitol, fructose, erythritol, indicated the predominance of the HBD_2 complexes, D standing for the carbohydrate. By the addition of sufficient mannitol or fructose it may be possible to titrate boric acid at a pH of 6.

L. Ambert, Compt. Rend., 108, 1016-1017, states that it is confirmed that mannitol, erythritol, dextrose, levulose or galactose, when mixed with a small quantity of boric acid or a diborate, the solution is strongly acid. He also finds that arabinose, arabinitol, dulcitol and mannitol form similar acid solutions. He concludes that polyhydric alcohols which contain a primary alcoholic function combine with boric acid to form energetic conjugated acids which decompose carbonates.

The carbohydrates which will activate boric acid to form the acid complexes which will combine with the amino-aromatic bases to form the salts of the present invention include polyhydroxy aldehydes or aldoses and polyhydroxy ketones or ketoses, and the alcohols derived from them by reduction, and the inner ethers of such alcohols derived by splitting off one or two molecules of water from these alcohols.

The term carbohydrates as used herein also includes those substances which yield the aldoses and ketoses above named when hydrolyzed by treatment with mineral acids or through enzymatic action.

The general formula for the aldoses may be stated to be $CH_2OH(CHOH)_nCHO$. For the purposes of this invention, n represents the number 2 or a greater number.

The general formula for the ketoses is

where n represents 1 or a greater number.

The carbohydrate alcohols contemplated in the present invention have the formula

where n represents the number 2, or a greater number.

The polysaccharides include the di-, tri- and

tetra-saccharides, and have the general formula of $(C_6H_{10}O_5)_nH_2O$, where n may be 2, 3 or 4.

The monosaccharides, aldoses, are known as monoses and those containing the ketone group are known as ketoses. According to the number of carbon atoms the monosaccharide carbohydrate contains it is classified as tetrose, pentose, hexose, heptose, octose and monose.

While this invention concerns itself, principally, with the carbohydrate-boric acid complexes formed from the hexoses, the alcohols derived from these hexoses, the hexitols, and the inner anhydrides of these hexitols, the hexitans and the hexides; the invention comprehends likewise, the use of all carbohydrates capable of activating boric acid to a greater degree of acidity, and/or because of the alcohol nature of the carbohydrate substance or of its ether structure, is capable of rendering the newly formed salt of the complex of a greater degree of solubility in water or in other solvents than the basic substance itself.

The tetroses include erythrose; its ketonic form erythroketose; and its alcohol, erythrol.

The pentoses include arabinose, ribose, xylose and the alkyl pentoses, such as rhamnose (methyl pentose, $(C_5H_9(CH_3)_3O_5$); the respective ketones of the foregoing, and their alcohols, such as adonitol, derived from ribose.

The hexoses include glucose (dextrose), gulose, manose, galactose; their ketone forms, such as fructose (laevulose), sorbose, formose, b-acrose, rhamnosehexose ($C_6H_{11}(CH_3)_3O_6$), and their alcohols, which include sorbitol, and mannitol, derived from dextrose; dulcitol, derived from galactose; and mannitol is also obtained on reducing mannose and laevulose.

The heptoses include the mannoheptose, alpha and beta glucoheptose, galactose, and the keto forms such as fructo-heptose; also rhamnoheptose (methyl heptose) $C_7H_{13}(CH_3)_3O_6$. The heptose alcohols include persitol which is the same as d-mannoheptitol.

The octoses include mannooctose, alpha and beta glucooctose and its alcohol octitol.

The nonoses include mannononose and glucononose.

The disaccharides include maltose, lactose, melibiose. Among the trisaccharides are included raffinose, gentianose, melezitose.

Among the polysaccharides suitable for the purposes of the present invention I have also found that certain soluble derivatives of cellulose compounds, such as methyl cellulose and hydroxyethyl cellulose, which form highly viscous fluids with water, are also capable of causing an increased dissociation of boric acid and impart to their solutions a strongly acid reaction.

The inner anhydrides of the carbohydrate alcohols may be of the monoanhydride or dianhydride types. The dianhydride of a hexitol, for example, has the general formula

These anhydrides include mannide and isomannide and sorbide $-C_6H_8O_2(OH)_2$; mannitan and sorbitan $-C_6H_8O(OH)_4$; also the dianhydride of erythritol.

Among the carbohydrate alcohols is also included pentaerythritol $-(CH_2OH)_3:C(CH_2OH)_2$, which has considerable activating power on boric acid.

The carbohydrates contemplated in the present invention also include the so called "enol" com-

pounds, which are formed when dextrose, mannose and fructose are converted into an enol,

in weakly alkaline solutions.

In the formulation of the compounds of this invention between amino organic bases and boric acid activated by a carbohydrate, depending on the case, I may use an excess of the carbohydrate over the amount of boric acid, or I may use an excess of boric acid over the carbohydrate. Thus, in the case of a weaker base, I would use a greater amount of both, the boric acid and the carbohydrate, so that the excess of either would help the formulation of the complex. I may use enough of the basic substance so that it will combine in at least one molar proportion to the boric acid present and there may also be an excess of boric acid, so that a complex may form on the type of a borax compound, the formula for the product being $\text{R.HBD}_x \cdot (\text{B}_2\text{O}_3)_n$; x and n being at least 1.

Where one molar equivalent of the organic base is linked to one molar equivalent of boric acid, the formula would be R.HBD_x , x being at least one, D standing for the carbohydrate, R for the organic base.

Where a suitable solvent would permit, I may use an excess of the basic substance over the amount of boric acid present than is required to permit of their unimolar combination. Such preparations may be used by themselves, as for external applications; or they may be utilized as stock solutions, the solution being properly diluted with the same or with another solvent to reduce the active substance to its suitable concentration for the particular purpose. Additional carbohydrate and boric acid may be added as required to make up a suitable solution for requisite use.

In making up the solutions of an amino organic basic substance linked to boric acid activated by a carbohydrate sugar or alcohol or inner ether of a carbohydrate alcohol, I may cause the reactants to combine in a suitable vehicle, such as water, glycerol, a glycerol ether such as ethyl, methyl or other suitable alkyl ethers of glycerine; an alcohol, such as ethyl alcohol, iso-propyl alcohol; the glycols, such as propylene glycol, diethylene glycol, diethylene glycol monethyl ether and other suitable glycol derivatives; a solution of sorbide, sorbitan and the like. The formation of the compound may also take place in a mixture of water with any of the above solvents, or mixtures of the solvents.

A solution thus prepared may be ready for use or may be evaporated to dryness from a suitable vehicle, or the formed compound may be precipitated from such a vehicle by virtue of the fact that it is insoluble or sparingly soluble in the vehicle employed.

The amino organic basic compound may be linked to the carbohydrate-boric acid complex in the same solution in which the complex is originally formed, or the complex may be first prepared separately and then used as the acid substance to which the organic base is to be linked. All of the reactants may be triturated in a little water and then mixed with acetone, or may be triturated with acetone only or with another volatile vehicle and then allowed the volatile vehicle to evaporate under a moderate heat, so that the heating of the components in the presence of the volatile vehicle in which, preferably, the organic base is soluble, promotes the formation

of the final product, the process of heating also volatilizing the vehicle.

Some carbohydrate-boric acid complexes may be formulated by first triturating the carbohydrate with the boric acid, when frequently a reaction sets in at once, indicated by the formation of a gummy, stringy mass, then followed by the application of a moderate heat, such as by placing the container over a low flame hot plate; the heating soon causing the combination to melt, and further heating driving off the water of the reaction, some of the water derived from the orthoboric acid in its conversion to the metaboric acid, and some derived from the reaction between the H's of the OH of the reactive alcoholic groups of the carbohydrate molecule and the O of the metaboric acid. The inorganic basic substance may be stirred in at this point, before the water of the reaction has been completely expelled, or it may be incorporated into the resinous mass generally formed at the end of the reaction, and the new compound formed by fusion, followed by its dissolution in a suitable vehicle for recrystallization or for direct use, as desired.

It is also possible to cause the formation of the carbohydrate-boric acid complex as described above, and, while the water of formation is being expelled and reactant mass is still in a fluid state, the amino organic basic substance may be dissolved in a volatile vehicle, and the solution mixed with the molten and still liquid complex material. In some cases the whole may be taken down to dryness at a moderate heat, expelling the last traces of the solvent vehicle under reduced pressure, or removing the vehicle all the way under reduced pressure. In other cases it is possible to cause a precipitation of the formed compound, the amino organic salt of the carbohydrate-boric acid complex, filtering off the precipitated mass and then drying it, expelling the final traces of the solvent under reduced pressure.

It is also possible to neutralize the acid radicle of a salt of a particular amino organic compound by adding a sufficient amount of a suitable alkaline substance, such as sodium hydroxide, sodium carbonate, potassium carbonate, or sodium bicarbonate, in an equivalent amount to fully combine with the acid present, and then adding to the base, either precipitated or in solution while freed from the original acid radicle, the proper amount of the desired carbohydrate boric acid complex, previously prepared in solution or solid form, to produce the new salt.

Another method of forming the newly developed salts of amino organic compounds with carbohydrate-boric acid complexes is by double decomposition. A suitable amount of the particular complex acid is first formulated in solution form, the acidity of the complex is then neutralized with an equivalent amount of alkali or other basic radicle. This alkaline or basic salt is added to a solution of the basic organic substance linked to some acid radicle will either form an insoluble salt in the vehicle employed with that acid radicle, or will cause an ionic transformation to indicate the formation of the salt of the initial organic base now linked to the carbohydrate-boric acid complex radicle.

Among the amino organic compounds that may be used to form the salts of the present invention are included generally any such amino compounds capable of reacting with an acidic substance of the nature described, such as aniline, para amino phenol, para methyl amino phenol (metol), and the like.

Among the amino compounds of the anaesthetic group the following may be listed: procaine, butyn, diethylamino propyl para amino benzoate, dipropylaminoethyl para amino benzoate, dimethyl amino ethyl para butyl amino benzoate (pontocaine), eucupin, nupercaine, and, in general, the alkyl and alkamine esters of amino benzoic acid. This group also includes similar compounds wherein the NH_2 grouping on the benzene ring is in other than the para position, and anaesthetics of the type wherein the aromatic nucleus is other than benzoic acid, such as cinnamic acid and the like. It also includes compounds of this type wherein the esterifying alcohol may be of the secondary type instead of the customary tertiary type, such as mono ethyl amino propyl para amino benzoate and the like, mono butyl amino propyl para amino benzoate and the like.

Among the amino organic compounds of the vaso constrictor type of substances may be listed the following: epinephrine, epinine, neo synephrine, ephedrine, ephetonine, tyramine, cobefrine and other similar compounds, consisting, in general, of amino aromatic compounds, hydroxylated or non-hydroxylated on the benzene nucleus and having an amino alcohol chain or an alkyl amino chain, methylated or non-methylated.

Among alkaloidal amino organic substances which may be used for the purposes of the present invention the following may be listed: caffeine, theobromine, veratrine, quinine, atabrin, ephedrine, brucine and others.

Of the so-called surface anaesthetic amino organic compounds, the following may be listed: benzocaine, butesin, iso-propyl para amino benzoate, orthoform (methyl meta-amino para-oxybenzoate) iso-butyl para amino benzoate and the like.

Among the sulfa compounds which are also capable of combining with the carbohydrate-boric acid complexes described, may be listed, generally, the amino sulfonyl amides such as sulfanylamide, sulfapyridine, sulfathiazole and sulfadiazine.

Numerous other amino organic compounds are suitable to be linked to the carbohydrate-boric acid complexes to form new and useful substances, some having a therapeutic effect and others suitable for industrial use, such as in photography and other uses.

The salts of the present invention are, in some instances of a balsamic nature, or of a resinous type, or may be of a pulverizable powder, or may be of a vitreous character. Generally they melt or soften easily on the application of heat of the boiling water bath or a low flame hot plate.

Following are a number of examples illustrating the foregoing principles. These examples are representative and are not intended to be limitative, and many more of the same or other compounds and in different proportions and combinations are possible.

As an example of how to formulate a dimannito-boric acid complex by the direct union of the ingredients, the following may be given: 72.8 gms. of mannitol (0.4 M.) may be triturated with 12.4 gms. of boric acid (0.2 M.) in a mortar, when soon combination begins to take place as is evidenced by the formation of a gummy stringy material. When the material is then transferred into a beaker, placed over a low flame hot plate, it soon becomes pasty and liquefies. As the water is being driven off, the material becomes resinous. When the water in the equivalent of 3 moles is

driven off, an amber, resinlike material is obtained. The material now weighs 75.2 gms., having lost 10.0 gms. of water. (The theory loss should be 10.8 gms.)

5 The above mannitolboric resin (two equimoles mannitol to one equimole of boric acid) may be dissolved in water and a suitable amount of an organic base may be stirred in and heated until the formation of a salt is obtained, or a base may be incorporated by fusion. Thus, 18.8 gms. of the resinous material, the dimannitoborate may be melted over a low heat hot plate and 5.9 gms. of procaine base (0.025 M.) may be stirred in. On removing the beaker from the hot plate and stirring the mix, the material assumes an amber, clear, transparent, balsamic resinous appearance. On cooling, the mass becomes vitreous, amber resin. The material dissolves easily in water on warming, giving an acid reaction to litmus. Ammonium hydroxide precipitates the procaine base from this solution.

Another method of preparing a mannitolboric acid complex is as follows: 14.56 (15) gms. of mannitol (0.08 M.) are mixed with 3.72 gms. of boric acid (0.06 M.) in the presence of 5 cc. of water, and the mix is boiled for a few minutes. 100 cc. of isopropyl alcohol are then added and stirred, when the entire mass becomes a white paste. This is filtered and washed several times with isopropyl alcohol and then dried. A white pulverizable powder is obtained. This acid complex may be dissolved in water and a suitable organic compound may be linked to the acid in suitable amount.

35 When 5 gms. of the above powder are dissolved in 75 cc. of water and brought to a boil, 2.36 gms. of procaine base may be stirred in until solution takes place. The solution has a pH of 6.1 brom thymol blue.

40 When in the above formulation of the mannitolboric acid 5 gms. of benzocaine are dissolved in the isopropyl alcohol and mixed with the carbohydrate boric acid complex, and the filtered mass is dried, a pulverizable powder is obtained. At least one gram of this material may be dissolved in 100 cc. of water on heating and it produces a surface anaesthetic. The amount of benzocaine thus dissolved in water is considerably in excess of the normal solubility of benzocaine in the same medium. The solution remains stable long enough to be used at room temperature.

45 When 3 gms. of this benzocaine-mannitolborate powder is dissolved in 100 cc. of water containing 5 gms. procaine base linked to a suitable acid, the solution remains stable for some time.

To indicate how procaine base may be combined in unimolar equivalents with boric acid, under suitable conditions, and how it may be rendered soluble, in accordance with the principles of the present invention, the following may be given: 60 4.72 gms. of procaine base (0.02 M.) are dissolved in ethyl alcohol and 1.24 gms. of boric acid (0.02 M.) are stirred in and the solution is evaporated to dryness. A hard mass is obtained which does not dissolve in water quite readily. It softens on the application of moderate heat over a low flame hot plate. When 7.28 gms. of mannitol (0.04 M.) are added and the beaker warmed on the hot plate below the boiling point of water, solution soon takes place and register a pH of about 7.1 brom thymol blue. The solution is made up to 100 cc. with water.

70 10 cc. of the above solution requires, for titration in the presence of 15 cc. of acetone, 4 cc. of a 0.5 N sodium hydroxide solution, equivalent to

1.24 gms. of boric acid, the same amount originally used. The use of acetone in this titration is to allow the base, as it is being freed by the addition of the alkali, to remain in solution during the titration. The addition of NH_4OH precipitates the procaine base from the aqueous solution.

The following additional examples are presented:

Example 1.—7.28 gms. of sorbitol (0.04 M.) and 1.86 gms. of boric acid (0.03 M.) are dissolved and boiled for several minutes in 5 cc. of water and 1.65 gms. of benzocaine (0.01 M.) are stirred in. Soon the benzocaine melts and the heating is continued for several minutes. 50 cc. of 85% of sorbide may then be added and the solution brought to a boil, the benzocaine going into solution. Instead of benzocaine, 1.67 gms. of orthoform may be used, or 1.79 gms. of propoescin may be used.

Example 2.—7.28 gms. of mannitol, sorbitol or dulcitol (0.04 M.) and 1.86 gms. of boric acid (0.03 M.) and 1.67 gms. of orthoform may be formulated and combined in water and the solution may remain stable long enough to be used.

Example 3.—Triturate together 7.28 gms. of sorbitol (0.04 M.), 1.24 gms. of boric acid (0.02 M.). A gummy white paste is formed. When 2.36 gms. of procaine base (0.01 M.) are stirred in and warmed on the water bath, a white balsamic material is obtained which dissolves easily in water and gives an acid reaction to methyl red.

Under these conditions, a lower pH solution is obtained, conducive to a greater stability of the solution than when a 5 molar equivalent of H_3BO_3 is used to one equivalent of procaine base as it obtains commercially, and has a pH of about 8.2 to 8.4 cresol red. A lower boric acid content is likewise desirable when the product is used for injection purposes. The above method represents a fusion method of obtaining a salt of a carbohydrate alcohol-boric acid complex.

Example 4.—Triturate 3.64 gms. (0.02 M.) of dulcitol with 1.24 gms. (0.02 M.) of boric acid and 236 gms. of procaine base with acetone and evaporate to dryness on the water bath. A light colored balsamic resinous material is obtained which, when dissolved in water and made up to 100 cc., registers a pH of about 6.1-6.3 brom thymol blue.

Example 5.—3.64 gms. of mannitol (0.02 M.) are rubbed together with acetone and 2.00 gms. of boric acid and 3.8 gms. of procaine base and taken down to dryness on the water bath. A balsamic mass is formed which becomes vitreous when cooled.

Example 6.—7.28 gms. of sorbitol (0.04 M.) and 1.86 gms. of boric acid (0.03 M.) and 1.65 gm. of benzocaine (0.01 M.) are triturated with acetone and taken down to dryness over the water bath. A balsamic substance is obtained which dissolves easily in 85% of sorbide solution in water.

Example 7.—3.64 gms. (0.02 M.) of sorbitol are triturated with 0.62 gm. (0.01 M.) of boric acid in acetone and taken down to dryness, forming a clear balsamic substance. This disorbitol monoborate dissolves easily in water and when made up to 100 cc. may be titrated in the presence of phenolphthalein to indicate the full presence of the originally taken boric acid.

When 2.36 gms. of procaine base (0.01 M.) is stirred into the above mixture of sorbitol and boric acid and taken down to dryness, a balsamic, transparent material is obtained which dissolves on warming in water and has a pH of about 6.9-7.1 bromthymol blue.

Example 8.—1.86 gms. of boric acid (0.03 M.)

and 3.64 gms. of mannitol (0.02 M.) are dissolved and 2.36 gms. of procaine base are stirred in, dissolving easily. The solution is made up to 100 cc. with water. 5 cc. of this solution requires 10 cc. of 0.1 N sodium hydroxide for titration in the presence of some additional mannitol. This is equivalent to 1.24% of free or uncombined boric acid, indicating a balance of 0.62 gm. of boric acid as combined with the procaine base present in unimolar combination.

A possible formula for the above compound would be $\text{R.HBD}_2\text{B}_2\text{O}_3$, R standing for procaine base, or for another amino organic base similarly reacting and similarly combined. When only a unimolar equivalent of the boric acid is present to the procaine base, the possible formula is R.HBD_2 .

When 5 cc. of the above 0.03 M. solution of boric acid are titrated in the presence of 15 cc. of acetone, 15 cc. of the 0.1 N NaOH are required, accounting for the full amount of 1.86 gms. taken originally in the formulation.

Example 9.—Dissolve 36.4 gms. (0.2 M.) of mannitol and 6.2 gms. (0.1 M.) of boric acid in about 10 cc. of water and boil for several minutes. Separately dissolve 23.6 gms. of procaine base (0.1 M.) in about 150 cc. of acetone and bring the two solutions together. The containing vessel is placed on the water bath and the acetone driven off as the procaine base combines with the mannitol-boric acid. The combined solutions remain clear for a little while until precipitation of the procaine mannitol borate begins.

The evaporated material is a resinous, vitreous, brittle substance, becoming balsamic on warming. The material dissolves easily in the water and is of an alkaline reaction.

Example 10.—Dissolve 14.56 gms. of mannitol (0.08 M.) and 2.48 gms. of boric acid (0.04 M.) in 5 cc. of water and separately dissolve 4.72 gms. of procaine base in 100 cc. of acetone. Mix both solutions and stir until precipitation takes place. The precipitate is filtered off and dried to a white powder, pulverizable but easily softening on warming. The water solution of this procaine mannitol borate is acid in reaction. Some of the reactants escape in the filtrate.

Using more of boric acid affords a more vitreous material when evaporated to dryness. The solution is also more acid, as when, for instance, a 5 molar concentration of boric acid is used (3.10 gms.) to two molar equivalents of mannitol (3.64 gms.) to one molar equivalent of procaine base (2.36 gms.). The solution in water registers a pH of about 5.7-5.8, methyl red, in 100 cc. of water, as against 8.2-8.4 cresol red for the five molar equivalent of boric acid to one of procaine base.

Example 11.—5.943 gms. of raffinose ($\text{C}_{18}\text{H}_{32}\text{O}_{16.5}\text{H}_2\text{O}$, mol. wt. 594.33, are dissolved in 75 cc. of water together with 1.86 gms. (0.03 M.) of boric acid and 2.36 gms. of procaine base stirred in until the procaine goes into solution. The solution is alkaline to bromthymol blue and the procaine may be precipitated by the addition of NH_4OH . This is an example of a polysaccharide, a trisaccharide, activating boric acid in solution, so that procaine base may react with it in a proportion less than a 4 molar equivalent of boric acid to one of procaine base.

Example 12.—Similarly, procaine base may be combined with rhamnose, $\text{C}_6\text{H}_{12}\text{O}_6\text{H}_2\text{O}$, mol. wt. 182. Using 3.64 gms. (0.02 M.) of rhamnose to 2.36 gms. of procaine base (0.01 M.) to 1.24 gms. of boric acid (0.02 M.), the solution has an alka-

line reaction. This is an example of using a methyl pentose to activate boric acid.

Example 13.—1.82 gms. of rhamnose (0.01 M.) are triturated with acetone and 1.86 gms. of boric acid (0.03 M.) and 1.72 gms. (0.01 M.) of sulfanilamide and taken down to dryness on the steam bath. A reddish amber material is obtained, the powder resembling shellac.

Example 14.—In the above described process of trituration with acetone and evaporating to dryness on the water bath, sorbitan may be substituted for the carbohydrate hexitol.

Thus, 7.56 gms. (0.04 M.) of sorbitan and 1.24 gms. (0.02 M.) of boric acid are triturated in acetone with 2.36 gms. of procaine base previously dissolved therein. On taking down to dryness on the steam bath, a balsamic resinous substance results, which is easily soluble in water.

Example 15.—3.28 gms. (0.02 M.) of sorbitan, 2.48 gms. (0.04 M.) of boric acid and 1.65 gms. of benzocaine are triturated in acetone. When placed on the water bath and warmed the material dissolves. When the solution is taken down to dryness, the evaporated mass presents a light gummy mass, hardening on cooling and dissolving easily on warming in 50 cc. of ethyl glycerine.

Similarly, the sulfonamide compounds of sorbitan borate may be prepared by trituration of the ingredients with acetone and taking the material down to dryness on the water bath.

Example 16.—3.28 gms. of sorbitan (0.02 M.) and 1.86 gms. of boric acid (0.03 M.) are triturated in about 50 cc. of acetone with 1.72 gms. of sulfanilamide or with 2.49 gms. of sulfapyridine, or 2.55 gms. of sulfathiazole or 2.50 gms. of sulfadiazine ([0.01 M.] of base in each instance). The sulfanilamide compound forms a balsamic resinous mass on being taken down to dryness. The sulfapyridine forms a white gummy mass; sulfathiazole a hard mass becoming gummy on heating on the water bath; sulfadiazine a white hard mass. The sulfanilamide compound dissolves easily in water on warming. The sulfapyridine and sulfathiazole compounds dissolve in ethyl glycerine on warming on the water bath. The sulfadiazine compound dissolves in 100 cc. of equal volumes of ethyl glycerine and 85% of sorbite solution in water.

Example 17.—An important preparation may be prepared by dissolving 1.64 gms. (0.01 M.) of sorbitan plus 1.86 gms. of boric acid (0.03 M.) and 1.72 gms. of sulfanilamide in about 10 cc. of alcohol, then mixing the solution with 40 cc. of the commercial collodion used for application to the skin. 1.65 gms. of benzocaine may be used in place of or together with the sulfanilamide in the above preparation.

Example 18.—3.60 gms. of dextrose- $C_6H_{12}O_6$ (0.02 M.), 2.48 gms. of boric acid (0.04 M.) and 2.36 gms. of procaine base (0.01 M.) are triturated with acetone and taken down to dryness on the water bath. A hard mass is obtained, white and solid, which softens to a doughy mass on the application of a moderate heat, as when placing the container over a low flame hot plate or immersing the container in boiling water. The material dissolves in water, giving a pH of about 7.1-7.3 bromthymol blue.

The formation and the solution of the procaine dextroseborate may also be obtained by mixing the ingredients in about 75 cc. of water and warming the solution at about 170° F. and below the boiling point of the solution. Combination takes place easily.

Example 19.—Using 1.65 gms. of benzocaine in 75 butyloxyquinoninic acid diethyl ethylene-

the foregoing example, instead of procaine, and triturating with acetone and taking down to dryness, a grayish amber powder is obtained, pulverizable and dissolving in 100 cc. of glycerine.

Example 20.—Substituting 1.72 gms. of sulfanilamide for the procaine in Example 18, and triturating in acetone and drying over the hot water bath, a slightly pinkish gray powder is formed, pulverizable and dissolving easily in water where it has an acid reaction.

Instead of dextrose, in the foregoing examples, laevulose may be used.

Example 21.—10.32 grams of metol sulphate ($(HO.C_6H_4.NH.CH_3)_2.H_2SO_4$ -p-methyl amino phenol sulphate (mol. wt. 344) representing 0.03 molar equivalents of the salt, equal to 0.06 molar equivalents of the metol base, may be ground into a paste with 3.18 gms. of Na_2CO_3 (0.03 M.) and placed on the water bath and stirred to drive off the CO_2 gas, for several minutes. A small amount of sodium sulphite may be present. Separately, 7.44 gms. of boric acid (0.12 M.) and 43.68 gms. (0.24 M.) of mannitol are dissolved and boiled in 150 cc. of water. There are, therefore, 2 molar proportions of boric acid to one molar proportion of metol base and two molar equivalents of the mannitol to one of the boric acid.

Separately are dissolved 44 gms. of sodium bisulphite in 100 cc. of water and 115 gms. of potassium carbonate stirred in. A portion of the potassium carbonate is neutralized by the acid bisulphite with the formation of the double salt of sodium potassium sulphite, $NaKSO_3$, and the balance of the potassium carbonate is left to impart the desired alkalinity to the solution. 5 gms. of potassium bromide are dissolved in this solution.

The mannitoboric acid solution is added to the metol solution neutralized with the sodium carbonate and this is then added to the carbonate-sulphite solution. The final volume is made up to 500 cc. and it constitutes a developing bath for about half gallon of final volume. The addition of 20 gms. of hydroquinone and stirring brings out the metol hydroquinone compound and the stock solution, when properly diluted, with three volumes of water, dissolves and mixes easily.

Instead of the sodium carbonate, sodium acid carbonate may be used to neutralize the acid radicle of the metol sulphate. 5.04 gms. of $NaHCO_3$, or 3.40 gms. of $NaOH$ may be used to the above amount of metol sulphate.

Instead of mannitol, dextrose may be used to form the carbohydrate-boric acid complex in the above example. 43.20 gms. of dextrose may be used.

Example 22.—Caffein alkaloid, $C_8H_{10}O_2N_4.H_2O$, m. wt. 212.13. This alkaloid may be combined with a carbohydrate boric acid complex as follows: 2.912 gm. of mannitol (0.16 M.) and 2.48 gm. of H_3BO_3 are dissolved and boiled up in about 75 cc. of water. The addition of 2.12 gm. of caffeine alkaloid to the solution causes it to dissolve at once with the formation of caffeine mannitoborate. The solution is acid to M. R. This is an illustration of how less than one molar equivalent of the carbohydrate was used to activate the boric acid present, and the solution of the caffeine borate took place. Caffein is a weak base.

Example 23.—Nupercaine base,

13

diamide; m. wt. 379.72 may also form a salt of a carbohydrate boric acid complex 0.3432 gm. of the base (0.001 M.) may be stirred into a hot solution of 2.184 gm. of sorbitol (0.012 M.) and 0.186 gm. of boric acid (0.003 M.). On stirring the base soon dissolves. The solution made up to 100 cc. with water registers a pH of about 5.2-5.4 M. R.

Example 24.—The formation of pontocaine salt of a carbohydrate boric acid complex may be done as follows: pontocaine, para butyl amino benzoyl dimethyl amino ethanol,

m. wt. 300.68. 0.60136 gm. of pontocaine HCl is dissolved in 30 cc. of water; 0.106 gm. of Na_2CO_3 (0.001 M.) is used to precipitate the nupercaine base, which is then redissolved in a previously prepared solution of 0.372 gm. of boric acid (0.006 M.) and 2.184 gm. of sorbitol (0.012 M.). Solution with the formation of pontocaine sorbitol borate takes place at once. The solution is made up to 100 cc. with water and it then registers a pH of about 5.5-5.6 M. R. Color Chart.

Example 25.—The formation of butyn salt of a carbohydrate boric acid complex may be illustrated as follows: butyn,

m. wt. 710.58. 0.7105 gm. of butyn sulphate (0.002 M.) is treated in 50 cc. of water with 0.106 gm. of Na_2CO_3 (0.001 M., but 0.002 N) to precipitate the butyn base. This may be readily dissolved in a previously prepared solution of 0.248 gm. of H_3BO_3 (0.004 M.) and 1.456 gm. of sorbitol (0.008 M.). Made up to 100 cc. with water, the solution registers a pH of about 5.1-5.4 M. R. Color Chart.

Example 26.—To illustrate the formation of eucupin salt of a carbohydrate boric acid complex, the following may be done: eucupin alkaloid, isoamyl hydrocupreine, $\text{C}_{24}\text{H}_{34}\text{O}_2\text{N}_2$, m. wt. 382.28.

1.9111 gm. of eucupin base (0.005 M.) may be stirred into a previously prepared solution of 1.86 gm. of H_3BO_3 (0.03 M.) and 7.28 gm. of sorbitol (0.04 M.), in which the eucupin base soon dissolves. The solution made up to 100 cc. with water indicates an acid reaction to M. R. indicator.

Example 27.—To illustrate the formation of a soluble cellulose carbohydrate boric acid complex, the following may be done. 3.72 gm. of boric acid (0.06 M.) may be dissolved in about 35 cc. of boiling water and added on to 100 cc. of a 10% solution of hydroxyethyl cellulose. The pH of the solution is promptly lowered and is definitely acid to M. R. 3.34 gm. of sulfanilamide (0.02 M.) may then be stirred and the solution warmed on the hot plate until the sulfanilamide dissolves. The solution may be poured out on a glass plate and allowed to dry until a film is formed.

An excess of a carbohydrate alcohol in the presence of less boric acid may render the solution of a strong base linked to such an acid complex more strongly acid than a similar solution containing more boric acid and less of the carbohydrate alcohol. For instance, a 2.36% solution of procaine base in a 3.64% solution of mannitol (0.02 M.) to a 1.86% solution of boric acid (0.03 M.) registers a pH of about 6.2-6.5 Brom Thymol Blue (Color Chart). When in a similar solution the mannitol content is doubled, to 7.28 gm. (0.04 M.), to 100 cc. of solution, the

14

pH is lowered to about 5.2-5.4; M. R. the amount of boric acid being lowered to 1.24 gm. in the 100 cc. solution (0.02 M.).

Less boric acid and more carbohydrate lowered the pH of the solution.

The various solutions illustrated in the above examples, as well as similar ones as of the present invention, either when used by themselves, or with various vasoconstrictors, may be used with antioxidants to prevent oxidation.

These antioxidants may be the usual bisulphites, sodium, or potassium bisulphite, sodium hydrosulphite, sodium metabisulphite. Acetone sodium bisulphite, the aromatic aldehyde sodium bisulphite compounds, such as benzaldehyde sodium bisulphite and the like may be used.

Sodium thiosulphate antioxidant may be used under certain conditions with the above amino aromatic salts of carbohydrate boric acid complexes alone, or it may be used in combination with the above bisulphites and their addition products, or with various mixtures of the same.

In connection with the sulfonamides, thiourea, allylthiourea and the like substances may be used as antioxidants.

The materials may be used either in solution form, or in powder; the carbohydrate-boric acid complexes may be previously prepared and added on to the base, to form the salt of the amino-aromatic compound with the complex upon dissolving in a suitable vehicle. Mixtures of the carbohydrate activators, boric acid, and the organic base may also be mixed in powder form, or stamped out into tablets, ready for final formulation when dissolved in a suitable vehicle as a solvent.

Example 28.—As an illustration of forming a salt of an amino-aromatic compound with a carbohydrate boric acid complex by the process of double decomposition, the following may be given: 4.72 gm. of procaine base (0.02 M.) may be combined in hot water with 1.84 gm. (0.04 M.) of oxalic acid to form monoprocaine oxalate.

Separately 29.12 gms. of mannitol (0.16 M.) may be dissolved in 75 cc. of boiling water with 4.96 gm. of H_3BO_3 (0.08 M.) and 1.482 gm. of $\text{Ca}(\text{OH})_2$ (0.02 M.) may be stirred into the mannitol borate solution when the calcium hydroxide soon dissolves with the formation of calcium mannito-borate. This solution is now added to the solution of the procaine oxalate, when calcium oxalate precipitates at once. The filtrate contains the formed by double decomposition procaine mannito-borate which may be isolated by removing the solvent.

Example 29.—0.065 gm. of epinephrine base powder may be dissolved in 0.1514 gm. of mannitoboric acid solution in 25 cc. of water. This is a one molar equivalent of the epinephrine base to two molar equivalents of the mannito-mono-boric acid. The solution registers a pH of about 6.5-6.7 brom thymol blue.

This completes the description of the products and processes of the present invention. It is to be understood that specific examples presented are intended to serve as illustrations of the general principles disclosed and are not intended to limit the invention in any way, as many variations and modifications may be made within the spirit and scope of the invention and without the use of the inventive faculties.

This application is a continuation in part of my copending application Serial No. 417,712, filed

November 3, 1941, for Anaesthetic solutions which has issued as Patent #2,382,546.

It is to be understood that the boric acid which is activated by the polyhydroxy compounds named in the specification need not be exclusively ortho-boric acid, but may also be in the form of meta-boric acid, boric acid anhydride, borax and other boric acid compounds.

What I claim is:

1. A salt formed of an amino-aromatic base from the group consisting of alkyl and alkamine esters of an amino-aromatic acid with boric acid, in the presence of an aliphatic polyhydroxy compound selected from the group consisting of erythritol, arabinose, arabitol, glucose, mannose, gulose, galactose, fructose, sorbitol, mannitol, dulcitol, glucoheptose, fructo-heptose, iso-mannide, sorbide, mannide, mannan, sorbitan and pentaerythritol.

2. A salt formed of procaine base with boric acid, in the presence of fructose.

3. A salt formed of butyn base with boric acid, in the presence of sorbitol.

4. A salt formed of benzocaine base with boric acid, in the presence of sorbide.

5. The process of forming a salt of claim 1, which comprises the steps of dissolving the amino-aromatic base in a volatile vehicle, triturating the solution with a mixture of boric acid and the aliphatic polyhydroxy compound and driving off the volatile vehicle by application of heat.

10

15

20

25

30

6. The process of forming a salt of claim 1, which comprises the steps of dissolving the amino-aromatic base in a volatile vehicle, triturating the solution with a mixture of boric acid and the aliphatic polyhydroxy compound and driving off the volatile vehicle at a temperature below the boiling point of water.

7. The process of forming a salt of claim 1, which comprises the steps of dissolving the amino-aromatic compound in a volatile solvent in which the formed salt is of limited solubility and combining the solution of said amino-aromatic compound in said volatile vehicle with a mixture of boric acid and the aliphatic polyhydroxy compound, stirring and heating the mixture and then removing the volatile solvent.

8. The process of forming a salt of claim 1, which comprises the steps of bringing together a salt of the amino-aromatic compound and a salt of boric acid combined with the aliphatic polyhydroxy compound, in a solvent, resulting in ionic transposition.

9. The process of forming a salt of claim 1, which comprises the steps of dissolving an oxalic acid salt of the amino-aromatic compound and adding to the solution of said salt a calcium salt of boric acid combined with the aliphatic polyhydroxy compound, filtering the precipitated calcium oxalate and removing the formed salt from the filtrate.
